UNITED STATES PATENT OFFICE

168,169

KITCHEN CABINET UNIT

Charlie Erwin O'Neal, Houston, Tex.

Application May 15, 1952, Serial No. 19,726

Term of patent 3½ years

(Cl. D33—19)

To all whom it may concern:

Be it known that I, Charlie E. O'Neal, a citizen of the United States, residing at Houston, State of Texas, have invented a new, original, and ornamental Design for a Kitchen Cabinet Unit, of which the following is a specification, reference being had to the drawings, forming a part hereof.

Fig. 1 is a perspective view of a kitchen cabinet unit showing my new design.

Fig. 2 is an end elevational view thereof.

I claim:

The ornamental design of a kitchen cabinet unit, as shown.

CHARLIE ERWIN O'NEAL.
